J. Smith
ATTORNEY

UNITED STATES PATENT OFFICE.

HENRY H. TAYLOR, OF BRIDGEPORT, CONNECTICUT.

STIFFENING-BAND.

SPECIFICATION forming part of Letters Patent No. 703,622, dated July 1, 1902.

Application filed April 17, 1902. Serial No. 103,390. (No model.)

To all whom it may concern:

Be it known that I, HENRY H. TAYLOR, a citizen of the United States, residing at Bridgeport, in the county of Fairfield and State of Connecticut, have invented certain new and useful Improvements in Stiffening-Bands; and I do hereby declare the following to be a full, clear, and exact description of the invention, such as will enable others skilled in the art to which it appertains to make and use the same.

My invention relates to certain new and useful improvements in stiffening-bands such as are commonly used for dress-collars and the like, and has for its object to provide a band of this description which shall be exceedingly simple and light, but at the same time possessing a proper degree of stiffness, such as would not be likely to annoy the wearer.

In the accompanying drawings, which form a part of this application, Figure 1 is an elevation illustrating the particular construction of stiffening element which I employ; Fig. 2, an elevation illustrating my completed stiffening-band, and Fig. 3 an elevation showing a modified form of stiffening.

Similar numbers of reference denote like parts in the several figures of the drawings. 1 is the stiffening element of my improvement, made from a single piece of fine well-tempered wire which is disposed throughout its length in zigzag fashion, so as to present at the top and bottom alternate loops 2 and openings 3. This stiffener is bound to a cloth facing 4 by means of upper and lower tapes 5 6, respectively, and end tapes 7 8, as shown at Fig. 2, so that it will be clear that the stiffening is afforded by the closed loops 2, uniformly distributed at the top and bottom,

while the openings 3, which are likewise uniformly distributed, afford a uniform flexibility throughout the length of the band.

The stiffening element may be disposed as is shown at Fig. 3, where I have shown a wire 45 9, crossed alternately at the top and bottom, so as to provide closed loops 10 and intermediate openings 11, and this construction of stiffener is within my invention, the gist of which latter rests in the idea of providing 50 alternate loops and openings along the top and bottom of the stiffener.

The cloth facing 4 merely provides a sort of lining, so that the stiffening element will not come into actual contact with the person 55 of the wearer, and I therefore do not wish to be limited in this respect, since the facing may be omitted and the stiffening element held in shape by means of the tapes above and below and at the ends.

Having thus described my invention, what I claim as new, and desire to secure by Letters Patent, is—

1. A stiffening-band comprising a wire disposed in zigzag fashion to form alternate loops 65 and openings at the top and bottom, said band being bound with tapes along the top and bottom and at the ends, substantially as set forth.

2. A stiffening-band comprising a wire disposed in zigzag fashion to form alternate loops and openings at the top and bottom, and a cloth facing secured to said band by tapes, substantially as set forth.

In testimony whereof I affix my signature 75 in presence of two witnesses.

HENRY H. TAYLOR.
